UNITED STATES PATENT OFFICE

97,338

DESIGN FOR A PLATE OR SIMILAR ARTICLE

Joseph Stetson, Chicago, Ill.

Application July 29, 1935, Serial No. 57,845

Term of patent 3½ years

To all whom it may concern:

Be it known that I, Joseph Stetson, a citizen of the United States and residing at Chicago, county of Cook, and State of Illinois, have invented a new, original, and ornamental Design for a Plate or Similar Article, of which the following is a specification, reference being had to the accompanying drawing, forming a part thereof.

The figure is a plan view of the plate, showing my design.

I claim:

The ornamental design for a plate or similar article, as shown.

In witness whereof I affix my signature.

JOSEPH STETSON.
